FIG. 1 is a side elevation of a combined bobeche and candlestick ornament embodying our new design, with the bulbs shown in dotted lines for illustrative purposes only.

FIG. 2 is a top plan view thereof as shown in FIG. 1.

FIG. 3 is a fragmentary perspective view as shown in FIG. 1 thereof.

FIG. 4 is a side elevation of a modified form of the combined bobeche and candlestick ornament as shown in FIG. 1.

FIG. 5 is a top plan view thereof as shown in FIG. 4.

FIG. 6 is a fragmentary perspective view thereof as shown in FIG. 4.

FIG. 7 is a side elevation of a further modified form of the combined bobeche and candlestick ornament shown in FIG. 1, with bulbs shown in dotted lines for illustrative purposes only.

FIG. 8 is a top plan view thereof as shown in FIG. 7.

FIG. 9 is a fragmentary perspective view thereof as shown in FIG. 7.

Several of the support arms are omitted in FIGS. 1, 4 and 7 for convenience of illustration only.

We claim:

The ornamental design for a combined bobeche and candlestick ornament, substantially as shown and described.
